DISPENSING CARTON

Palmer B. McConnell, Appleton, Wis., assignor to
 Marathon Paper Mills Company, Rothschild,
 Wis., a corporation of Wisconsin

Application March 19, 1936, Serial No. 69,711

7 Claims. (Cl. 206—58)

The present invention relates to dispensing cartons and particularly to a carton of the type for containing rolls of paper and the like, such for instance, as rolls of waxed paper from which the paper is dispensed in web form and torn in pieces of desired lengths against a cutter.

An object of the present invention is to provide a dispensing package adapted to hold a single roll of paper or other material so as to protect the same from dust and to permit the ready withdrawal of the paper web.

The invention further contemplates a package made from a single blank of material, which is scored and folded to provide a package of the requisite form and construction.

An important object of the invention is to provide a carton having a hinged front panel so as to permit ready grasping of the free edge of the paper web.

20 A further object of the invention is to provide a package which is economical to manufacture, easy to assemble, and efficient in use.

The above, other and further objects of the invention, will be apparent from the following description, the accompanying drawing and appended claims.

Embodiments of the invention are illustrated in the accompanying drawing and the views thereof are as follows:

30 On the drawing:

Figure 1 is a perspective view of a box embodying the present invention.

Figure 2 is a transverse vertical section of the box illustrated in Figure 1.

35 Figure 3 is a fragmental perspective view of one end of the box showing two end flaps interlocked.

Figure 4 is an end view of the box showing two more flaps in position.

Figure 5 is a plan view of the blank from which 40 the carton is made.

The blank is cut and scored to provide a top wall panel 14, rear wall panel 13, bottom wall panel 12, upper and lower front wall panels 15 and 11 and a hinged panel 10 overlapping the 45 upper front wall panel 15.

The top wall panel is provided with end flaps 20 which fold along lines 1 and are free along cut lines 1 and 2. The flaps are scored at their extremity to provide tuck-in flaps 21. Notches 50 25 are cut in flaps 20 to provide locking portions when the flaps are assembled.

The bottom wall panel 12 has no end flaps.

55 The rear wall 13 is scored along lines 6 to provide flaps 19. These flaps have L-shaped slits 28, 29 positioned near the fold lines 6 as shown in Figure 5. The upper edges of flaps 19 are cut to provide an inclined portion 39, a horizontal portion 40 and a stepped portion 41 to provide a suitable interlocking structure for tuck-in 60 flaps 21.

Slits 33, 34, and 35 are provided in the medial portion of the rear wall 13 to form a small flap 32, hinging on fold line 34, as shown in Figures 1 and 2. Flap 32 is depressible by the thumb in order to apply slight pressure to roll 46 as the 5 web is being withdrawn from the box.

The upper front wall panel 15 is scored along line F to provide a free flap 16 which is folded inside the box to overlie the roll 46 as shown in Figure 2. The front wall is scored along lines 8 10 to provide end flaps 22 which are provided with triangularly shaped notches 27 to form locking tongues 26.

A rectangular opening 45 is located in the medial portion of the top and front walls for the 15 purpose of accommodating the thumb of the user when the end of the web is grasped.

The upper front wall panel 15 is overlapped by a swingable panel 10 which is hinged along score line A. A tear-off blade 40 is scored to 20 the panel 10 so that its serrated edge will have the points of the serrations extending slightly beyond the edge of said panel. The tear-off blade may be fastened by any suitable means to the outside or inside of the panel 10. 25

Panel section 10 is provided with end flaps 17 which are foldable along score lines 4 and cut free along lines 3. The ends of flaps 17 act as stops to limit the outward swing of panel 10 as shown in Figure 4. When panel 10 is swung to 30 the dotted line position shown in Figure 4 the tips of flaps 17 contact the top wall as shown by the dotted lines and thereby limit the outward swing of panel 10. In my preferred box construction panel 10 does not swing out more 35 than about 45° out of the front panel plane.

It is to be understood that the invention is not restricted to the specific means disclosed for limiting the outward swing of the hinged panel. Any other suitable means such as, for example, 40 pieces of flexible tape or wire attached to the box and the panel may be used if desired.

The lower front wall panel 11 is provided with end-flaps 18 foldable along side lines 5. The flaps are cut at one edge along lines 42 and 43 to provide off-set portions adjacent the panel 10. 45 Triangular cut out notches 38 are provided on the other edge of the flaps to form locking tongues 24 which hold the panel 11 in fixed position.

The method of making a box from the blank 50 illustrated in Figure 5 is as follows:

The blank is folded into box-like form along scored lines B, C, D, E and F to form panels 10, 11, 12, 13, 14, 15 and 16. Roll 46 is placed within the panels with panel 16 folded thereover 55 as shown in Figure 2. End flaps 19 are then folded over the end of the box as shown in Figure 3 and tongues 24 are inserted in the L-shaped slots 29 thereby locking the lower front wall panel 11 in position. Tongues 26 of end flaps 22 are 60

then inserted in the L-shaped slots 28 thereby locking the upper front wall panel 15 in position.

Stop flaps 17 are then folded over the ends of the box as shown in Figure 4 and end flap folded 5 thereover and locked into position by means of tuck-in flap 21.

In using the carton it is simply held, say in the left hand, with the bottom 12 resting against the palm, the left thumb resting lightly on flap 10 32, and the fingers grasping the lower front wall panel 11. The thumb of the right hand is then inserted inside the hinged panel 10 in the vicinity of the cut out portion 45 which accommodates the back of the thumb. The hinging panel is swung out 15 sufficiently to permit grasping of the end of the web 47 which can then be drawn out to the required length. A slight pressure is then applied on flap 32 with the left thumb to hold the roll 32 rigidly and the web is cut off on the cutter blade 40. 20

20 After the web is cut the end portion thereof will be retained in the passage formed by panel 10 overlapping the front wall 15. End flaps 17 being in frictional engagement between portions of the outer closure flaps 20 and the inner flap 19 25 will restrain the outward swing of hinged panel 10 to such limited extent as to prevent the end of the cut web from folding back on itself and receding within the box. This construction therefore serves to retain the end of the web within 30 the passage for grasping by the fingers.

The box made in accordance with this invention is strong and rigid enough for all purposes intended, pleasing in appearance, and one which lends itself very readily for use in connection with 35 rolled waxed paper or other types of paper. The box is securely fastened together without the use of glue, paste, stickers, or like means thus making assembly rapid and economical.

The panels or walls have been designated as 40 front, bottom, rear, top and the like, but it is to be understood that this is for convenience only, and the invention is not to be construed as limited by designation of these parts in the manner mentioned.

45 It is to be understood that many changes may be made in the proportion of parts and equivalents may be substituted or used without departing from the spirit and scope of the invention.

I claim:

50 1. A box for a supply of a rolled web including a top, rear, bottom and front wall, said front wall extending short of the bottom wall, overlapping end flaps for closing the ends of said box, a hinged panel overlapping a portion of said front wall to 55 provide a passage therebetween for the web, said hinged panel having end portions movable in frictional engagement between overlapping portions of the said end flaps, said end portions being so constructed and arranged as to limit the outward swing of said hinged panel to such limited extent as to retain the end of said web within said 60 passage in position for manual grasping thereof.

2. A box for a supply of rolled web material including a top, rear, bottom and front panel, said 65 front panel consisting of an upper and lower panel portions, said upper panel portion having a folded flap portion the free end of same being adapted to overlie a roll contained within said box, the said lower panel portion terminating short of the 70 upper panel portion to provide a longitudinal slot for the passage of the web material, and a hinged panel integral with the said lower panel portion overlapping said slot and a portion of the upper front panel to provide a passageway for withdrawal of the web material.

3. A box for a supply of rolled web material including a top, rear, bottom and front panel, said front panel consisting of an upper and lower panel portions, said upper panel portion having a folded flap portion the free end of same being 5 adapted to overlie a roll contained within said box, the said lower panel portion terminating short of the upper panel portion to provide a longitudinal slot for the passage of the web material, a panel integrally hinged to said lower 10 panel portion and overlapping said slot, said hinged panel being provided with stop means at its ends to limit the outward swing thereof.

4. A box for a supply of rolled web material including a top, rear, bottom and front panel, said 15 rear wall having end flaps provided with slits for receiving locking tongues, said front panel consisting of spaced upper and lower panel portions, said upper panel portion having a longitudinally hinged flap portion adapted to overlie a roll contained within said box and having end flaps provided with locking tongues, said lower panel portion having end flaps provided with locking tongues and having a panel integrally hinged thereto, said hinged panel overlapping the upper 20 panel portion of said front panel.

5. A box for a supply of rolled web material including a top, rear, bottom and front panel, said rear wall having end flaps provided with slits for receiving locking tongues, said front panel consisting of spaced upper and lower panel portions, said upper panel portion having a longitudinally hinged flap portion adapted to overlie a roll contained within said box and having end flaps provided with locking tongues said lower panel portion having end flaps provided with locking tongues, a panel integrally hinged to said lower panel portion, said hinged panel overlapping the upper panel portion of said front panel and having 30 stop portions at the ends thereof for limiting the 35 outward swing of said panel.

6. A box for a supply of rolled web material including a top, rear, bottom and front panel, said front panel consisting of spaced upper and lower panel portions, said upper panel portion 45 having a longitudinally hinged flap portion adapted to overlie a roll contained within said box and having end flaps provided with locking tongues, said lower panel portion having end flaps provided with locking tongues and having a panel 50 integrally hinged thereto, said hinged panel overlapping the upper panel portion of said front panel, said rear wall being provided with end flaps having notches therein for receiving the locking tongues of the front panel portions, said top wall 55 having flaps overlying said end flaps and having a tuck-in flap for locking same in position.

7. A box for a supply of rolled web material including a top, rear, bottom and front panel, said rear wall having end flaps provided with slits for receiving locking tongues, said front panel consisting of spaced upper and lower panel portions, said upper panel portion having a longitudinally hinged flap portion adapted to overlie a roll contained within said box and having end flaps provided with locking tongues, said lower panel portion having end flaps provided with locking tongues and having a panel hinged thereto, said panel overlapping the upper panel portion of said front panel, said hinged panel having stop portions at the ends thereof folded over said interlocked end flaps and freely movable thereover into limiting contact with the top panel.
